[57] CLAIM

The ornamental design for an electrically conductive ribbon, as shown and described.

DESCRIPTION

FIG. 1 is a front elevational view of an electrically conductive ribbon showing my new design, the rear being a mirror image, and the ends being shown broken-away to indicate indeterminate length; and, FIG. 2 is a vertical cross-sectional view thereof, taken along line 2—2 of FIG. 1.

FIG. 1

FIG. 2
